(57) **CLAIM**

The ornamental design for an inductive charger, as shown and described.

DESCRIPTION

FIG. 1 is a top view of the inductive charger;

FIG. 2 is a bottom view thereof;

FIG. 3 is a rear view thereof;

FIG. 4 is a front view thereof;

FIG. 5 is a left side view thereof;

FIG. 6 is a right side view thereof; and,

FIG. 7 is a front, top, left side perspective thereof.

The broken lines showing the part between the circular base and the long thin rectangular plate are for the purpose of illustrating portions of the inductive charger that form no part of the claimed design.
